RECIPROCATING TRANSFER FOR ROTARY SHEET FEEDING MECHANISMS

Wendell William Jones, Pittsburgh, Pa., assignor
to Blaw-Knox Company, Pittsburgh, Pa., a corporation of New Jersey

Application May 28, 1947, Serial No. 751,018

3 Claims. (Cl. 271—53)

1

This invention relates to improvements in sheet feeding mechanisms to be used for feeding individual sheets to a rotary drum.

One of the objects of the invention is to provide a feeding mechanism which may be adjusted to feed sheets of various widths and various lengths accurately to the same place adjoining the drum in synchronism with the rotation of the drum.

Another object of the invention is to provide a sheet feeding mechanism designed to cooperate with sheets delivered to a feed table by a conveyor mechanism, without requiring that the sheets be first placed in a definite position on the feed table in order to insure that cooperation.

Another object of the invention is to provide a sheet feeding mechanism synchronized with a rotating drum provided with sheet gripping members on the drum and means for feeding the sheets accurately to a limited area in which they may be gripped by the grippers.

Other objects and advantages of the invention will be mentioned hereinafter or will become apparent from a perusal of the specification and drawings in which a preferred embodiment of the invention is illustrated and described.

As shown on the drawings:

Figure 1 represents a side elevation of an apparatus embodying my invention;

Figure 2 is a partial sectional view of the same apparatus shown in position to initiate a sheet feeding operation;

Figure 3 is a partial sectional view of the same apparatus shown in the position it occupies at the completion of a sheet feeding operation;

Figure 4 is an elevation of a portion of the sheet feeding mechanism;

Figure 5 is a plan view of the apparatus as shown in Figure 4; and

Figure 6 is a plan view of the sheet feeding table.

Referring further to the drawings the apparatus includes a rotatable drum 10 mounted for rotation in suitable bearings supported on the frame members a few of which such as 11, 12 and 13 appear in the elevational view in Figure 1. Other frame members for supporting the other end of the drum may be assumed.

Adjoining the drum and secured to related frame members including the upright 14 is a feed table generally indicated as 15 and which includes the side frame members 16 and 17 and the end frame member 18. The bed of the table on which the sheets may be deposited, prior to feeding, is preferably though not necessarily formed of a plurality of spaced apart wooden slats such as 19.

Extending upwardly between spaces provided therefor between the slats are a plurality of pusher fingers 20 which are rigidly mounted upon a cross plate 21 which may be adjustably se-

2

cured longitudinally of the feed table by means of bolts such as 22 extending through the longitudinal slots 23 in a plate 24 which is part of a carriage mounted for longitudinal reciprocation underneath the feed table. As is more clearly shown in Figure 3, the plate 24 is secured to brackets 25 and 26 which slidably embrace a pair of fixed longitudinally extending rods such as 27, one of which is best shown in Figure 3. It is apparent that by means of the mechanism shown, and about to be more fully described, the carriage structure consisting of the plates 21 and 24 and brackets 25 and 26 reciprocate under the table with only the fingers 20 extending above the surface of the feed table.

For reciprocating the feeding mechanism between the retracted position shown in Figure 2 and the forward position shown in Figure 3, I provide a sprocket gear 28 driven by means of the sprocket chain 29 which is in turn driven by sprocket chain 30 which may be, though not necessarily, connected with the driving mechanism of a printing machine which delivers printed sheets to the feed table. As shown on the drawings, another sprocket chain 31 is utilized for driving the drum 10.

The shaft of the gear 28 carries rigidly therewith radial crank arms 32 which are pivotally connected at 32' with connecting rods 33 which in turn are pivotally connected with pusher arms 34 and guide rods 35 whose lower ends are pivotally supported upon a bracket 36. Since the crank arms 32 rotate with the sprocket gear 28 it is apparent that continuous rotation of the gear 28 will effect the reciprocation of the feed fingers 20 which are connected with the carriage bracket 37.

In the feeding mechanism shown, the advanced or forward position of the carriage will always be the same, but inasmuch as the feed fingers 20 are adjustable thereon the mechanism is able to feed sheets of several different lengths to the pick up position on the drum. In Figure 2 the two extreme adjusted positions of the feed fingers 20 relatively to the carriage 37 are shown, one in full line and the other in dotted lines.

For guiding the leading edge of a sheet such as A to the drum I provide a curved plate 38 which terminates in proximity to the drum at the position where the gripping of the sheet is desired.

In Figure 3 there is shown a gripping finger 39 which is mounted for rotation with a rock shaft 40, the shaft extending parallel to the surface of the drum but slightly inside of its periphery. While the present invention is not confined to use with this type of gripping mechanism alone, the gripping mechanism selected indicates one suitable type which may be employed and which requires accurate positioning of the leading edges 60 of the sheets at the gripping position on the

drum. Without a detailed explanation of the mechanism of the gripping fingers it will nevertheless be perceived that upon rocking of the gripping finger into the drum interior the sheet may be released whereas when the gripping finger 39 is projected to the exterior of the drum it will clamp the leading edge of the sheet against the drum surface.

When the gripping mechanism of this character is employed it is important that the leading edge of a sheet when it is delivered to the drum be caused to lie flatly against the surface of the drum. Accordingly I provide a mechanism to make certain that this will result. A rock shaft 41, shown on an enlarged scale in Figure 5 will be mounted in suitable bearings on the machine frame adjacent the drum. Secured to this rock shaft at intervals will be a plurality of curved guide fingers 42. Keyed or otherwise secured to the rock shaft is an arm 43 pivotally connected by link 52 with a lever 44 which is pivotally mounted at 45 upon a bracket 46 connected to the frame member 12. A spring 47 is anchored to the upward extension 48 of the bracket 46 and is connected to the arm 44 at 49. This spring therefor serves to urge the lever 44 to rotate in a counter-clockwise manner as viewed in Figure 4, or in a clockwise manner as viewed in Figure 2 or 3. A cam 50 is secured to the end surface of the drum, as shown in Figure 4, adjoining each set of gripping members, and as these gripping members approach the position where they are intended to pick up a new sheet of paper the roller or cam follower 51 pivoted on one end of the arm 44 will strike the cam 50 and cause the lever 44 to rotate in a direction contrary to the force of the spring. This rotation of the lever 44, through the link 52 and arm 43 will cause the rock shaft 41 to rotate and cause the curved fingers 42 to swing toward the curved plate 38 and the drum, as shown in Figure 3, to engage the leading edge of the paper A and guide it into contact with the drum surface whereby the gripping fingers 39 may immediately thereafter grip the leading edge of such sheet.

As stated above, the function of these curved fingers 42 is merely to guide and to cause the leading edge of the paper sheet A to lie flatly against the drum surface, so that the sheet gripping fingers mounted on the drum may readily grasp the leading edge and clamp it against the drum surface. Therefore, the fingers 42, when projected toward plate 38, do not contact it but need only to rotate close enough to the curved surface 38, as shown in Figure 4, to accomplish the above function. It is not necessary to press the sheet A against the curved surface, nor do the fingers 42 in any way grip the sheet to advance it. When the fingers 42 are retracted there is even greater clearance between them and the curved plate 38, as shown in Figure 2, hence the fingers 42 do not impede the advance of the sheet as it is being advanced to the drum by the feed fingers 20.

The cam 50 is so positioned on the drum that after the gripping fingers 39 have gripped the sheet the cam 50 will pass beyond the roller 51 whereupon the spring 47 will retract the guide fingers 42.

In the operation of the device sheets of paper, perhaps just freshly printed, will be delivered by means of a conveyor belt 53 onto the feed table, whereupon the sheets will merely drop down and slide forwardly upon the slats. In the synchronized operation of the apparatus the feed fingers

20 will move forwardly to engage the rear edge of the sheet and slide the sheet A along the slats and thence along the curved plate 38 into proximity with the drum. As just explained the guide fingers 42 will guide and press the leading edge of the sheet against the drum surface in timed relation to enable the gripping fingers 39 at the correct instant to grasp the leading edge of the sheet.

Vertical guide members 54 and 55 may be adjustably positioned by means of slots such as 56 and bolts such as 57 near the lateral margins of the feed table to assist in guiding the sheets being delivered from the conveyor belt 53. However, it will be recognized that the feed fingers 20 upon contacting the rear edges of the sheets will properly "square" the sheets so that their leading edges will be presented properly to the drum gripping mechanism.

While I have described herein in considerable detail a preferred embodiment of the invention, for the sake of illustrating the nature of the invention and its mode of operation, it should be understood that the invention is not limited to the precise details of construction herein shown and described, but is susceptible of some variation and modification within the scope of the invention as defined in the appended claims.

I claim as my invention:

30 1. In combination, a rotatable drum, feed mechanism for feeding sheets to the drum comprising a feed table having longitudinal slots therein and having a forward edge terminating adjacent the drum, a reciprocating carriage mounted for movement below the table, feed fingers on the carriage extending upwardly through said slots to engage the rear edges of the sheets, the drum having rotatable gripping fingers for gripping the leading edges of the sheets, synchronized drive means for reciprocating said carriage in timed relation with the rotation of said drum for delivering the leading edges of sheets to the gripping fingers on the drum, means for adjusting said feed fingers longitudinally of said carriage, movable guide fingers pivotally mounted adjoining the drum and cam operated means for projecting and retracting said guide fingers respectively toward and away from said table edge constructed for projecting said fingers in timed relation to the rotation of the drum for guiding the leading edges of sheets to the drum surface into position to be gripped by the gripping fingers on the drum.

2. In combination, a rotatable drum, feed mechanism for feeding sheets to the drum comprising a feed table having longitudinal slots therein and having an upwardly curved forward edge terminating adjacent the drum, a reciprocating carriage mounted for movement below the table, feed fingers on the carriage extending upwardly through said slots to engage the rear edges of the sheets, the drum having rotatable gripping fingers for clamping the leading edges of the sheets to the peripheral surface of the drum, synchronized drive means for reciprocating said carriage in timed relation with the rotation of said drum for delivering the leading edges of sheets to the gripping fingers on the drum, means for adjusting said feed fingers pivotally longitudinally of said carriage, movable guide fingers mounted adjoining the drum, and cam operated means for projecting and retracting said guide fingers respectively toward and away from said curved edge constructed for projecting said fingers in timed relation to the rotation of the drum

for guiding the leading edges of sheets to the drum surface into position to be gripped by the gripping fingers on the drum.

3. In combination, a rotatable drum, feed mechanism for feeding sheets to the drum comprising a feed table having longitudinal slots therein, a reciprocating carriage mounted for movement below the table, feed fingers on the carriage extending upwardly through said slots to engage the rear edges of the sheets, the drum having gripping means including rotatable clamps for gripping the leading edges of the sheets, synchronized drive means for reciprocating said carriage in timed relation with the rotation of said drum for delivering the leading edges of sheets to the gripping means on the drum, means for adjusting said fingers longitudinally of said carriage, oscillatable curved guide fingers mounted adjoining the drum, and means

for oscillating said guide fingers constructed for projecting said fingers toward the drum in timed relation to the rotation of the drum for guiding the leading edges of sheets to the drum surface into position to be gripped by the gripping mechanism on the drum.
